Attorney

UNITED STATES PATENT OFFICE.

EARLE M. HUMPHREYS, OF NEW YORK, N. Y.

GAME PIECE.

Application filed August 29, 1924. Serial No. 735,024.

My invention relates generally to games played with movable pieces and particularly to games of chance in which two or more players may participate, and in which a die 5 or a plurality of dies are employed as the game device or devices, the preferable number of game pieces employed being three.

One object of my invention is to provide a set of pieces or dice for a game of this 10 character in which each player plays with or against the board and not with the other players.

A further object of my invention is to provide a plurality of dies, preferably three, 15 each having the same markings, which markings are preferably Chinese in character and may be taken from a well-known Chinese game played with pieces known as "tiles".

The different combinations developed by the throws of the dice can be readily calculated in view of the fact that each die has the same markings, and these combinations are indicated in the schedule of scoring 20 and non-scoring throws hereinafter set forth. In the present instance certain of these markings are duplicated so that each die, preferably of the usual square or cubical form having six sides, presents four different markings upon the respective sides of the same; certain of such markings being duplicated upon two separate sets of opposite faces of each die.

The rules of one type or character of game which may be played with this set of dice may provide that certain combinations appearing as the result of a throw are winning combinations; other combinations 25 are losing combinations; other combinations are blanks, in which the player is entitled to another throw, while still other combinations are termed "fizzles" and when thrown twice by any player, cause such player to lose the right of play until his next turn 30 in the regular order of play, which order may be established before commencement of the game.

These and other features of my invention 35 are more fully described hereinafter; reference being had to the accompanying drawings, in which:

Figure 1, is a perspective view of my improved playing pieces or dice, the several 40 views of the respective dies illustrating all of the characters to be found thereon, and

Fig. 2, is a view illustrating one of the dies developed, that is to say, with the sides spread out to indicate the markings thereon and their respective positions. 60

In the present instance, each of the dies indicated at A contain the following designs. One "wind", preferably displayed in green and indicated at 1; one "dragon", 65 preferably displayed in red and indicated at 2; two "circles", or "cash", preferably displayed in orange (or yellow), on opposite sides of the die, and indicated at 3, and two "sparrows", preferably displayed in blue, on opposite side of the die at right 70 angles to the "circles" or "cash", and indicated at 4.

Any number of persons may play a game 75 with my improved game pieces or dice, and the person whose turn it is to throw the dice (or "bones", as they may be termed), is known as the "wind". All the other players are known as "dragons". The game 80 may be termed a battle royal between the "wind" having the privilege or right of throw, and the "dragons".

Each combination displayed by the dice has a certain value, which when thrown 85 counts as a score for, or a penalty against the "wind", as indicated in the schedule or scoring table hereinafter set forth.

The purpose of the game as in other similar games of chance, is to gain the most 90 points, which may be totaled at the end of play. For the purpose of counting these points, poker chips, "Mah jongg" tiles, or other pieces of suitable unit and multiple unit value may be employed.

The procedure or method of play may be 95 as follows:

The "wind", chosen at the start of the play by the toss of a coin or in any other suitable manner, takes possession of the dice and begins the play by throwing the same 100 on a game board or other playing space. This may be done from the hand, or a dice cup may be employed, as desired. Each "dragon" advances as many chips or other unit pieces representing points as he desires 105 to risk on the "wind's" throw of the dice, placing them in a pile in front of his position, and the "wind" is obliged to cover exactly each amount so placed. It will be understood, of course, that any limit of play 110 may be established before the commencement of the game.

The dice are thrown by the "wind" player and the combination that turns up is scored in accordance with the schedule or scoring table hereinafter set forth; the chips or other markers being collected by the winning player, or players, or left on the board, as may be determined by reference to the schedule or score table. If the throw is one which causes the "wind" to lose the dice, i. e., to lose the right of play, they pass on to the first player to the left, who in turn becomes the "wind", with the rest of the players as "dragons". Any "wind" has the right of refusing to throw the dice, in which case they pass to the first player to his left, and so on as the play continues.

As shown in the following schedule or scoring table there are certain "no score" throws, classified as "fizzles" and "blanks", in addition to the winning and losing combinations.

Fizzle: Two "fizzles" lose the right of play for the "wind", unless a winning throw intervenes. A scoring throw succeeding one "fizzle", however, cancels the same. When two "fizzles" are thrown with no winning throw intervening, the player loses his turn and the dice pass on to a new "wind", and all markers or other counters then on the board or playing space are combined into a bonus pile in the center, and this bonus pile goes to the first player thereafter who wins with at least a double scoring throw; i. e., a pair of "winds" or better.

Blanks: A blank scores nothing, and has no effect upon any previous or subsequent throw.

The schedule or scoring table may be as follows:

40 *Winning throws.*

2 circles, 1 wind—wins chips and keeps dice.

2 sparrows, 1 wind—wins chips and keeps dice.

3 circles—wins double and keeps dice.

3 sparrows—wins double and keeps dice.

2 winds, 1 circle—wins double and keeps dice.

2 winds, 1 sparrow—wins double and keeps dice.

2 winds, 1 dragon—wins double and loses dice.

3 winds—wins 4 times and keeps dice.

55 *Penalty throws.*

2 circles, 1 dragon—loses chips and loses dice.

2 sparrows, 1 dragon—loses chips and loses dice.

2 dragons, 1 circle—loses double and loses dice.

2 dragons, 1 sparrow—loses double and loses dice.

2 dragons, 1 wind—loses double and keeps dice.

3 dragons—loses 4 times and loses dice.

No score throws.

1 circle, 1 sparrow, 1 wind—fizzle.

1 circle, 1 sparrow, 1 dragon—fizzle.

1 sparrow, 1 wind, 1 dragon—fizzle.

1 circle, 1 wind, 1 dragon—fizzle.

2 circles, 1 sparrow—blank.

2 sparrows, 1 circle—blank.

It will be understood, of course, that the 75 scoring values of the respective combinations referred to may be altered to suit any form of play or to change the character of the game. The present arrangement has been worked out on the basis that the probabilities of the throws range from the three "winds" or three "dragons" to the "no score throws", in inverse order.

While I have adapted certain distinctive markings taken from the tiles employed in 85 a well-known Chinese game, it will be understood that I do not wish to be limited to the exact markings shown, nor to the colors used; either one of which may be changed without affecting my invention or the 90 method of play; corresponding changes being made in the score sheet employed.

While I have shown the figures representing the markings as colored "green", "red", "orange" (or "yellow"), and "blue", respectively, it will be understood that such figures 95 may be shown in white or a single color, with the rest of the die face in the respective colors and arrangement without departing from my invention.

I claim:

1. A game comprising a plurality of dies, each having the same markings, each of said markings consisting of single devices, certain of said markings being duplicated, and all of said markings simulating the markings of the well known Chinese tile game.

2. A game comprising a set of three dice, each having the same markings, each of said markings consisting of single devices, certain of said markings being duplicated upon opposite sides of the dice at right angles to each other, and all of said markings simulating the markings of the well-known Chinese tile game.

3. A die or game piece comprising a six-sided cube having the following markings, a "dragon"; a "wind"; a pair of "sparrows" and a pair of "circles"; the "sparrows" and "circles" being in alignment circumferentially of the die.

4. A die or game piece comprising a six-sided cube having the following markings, a "dragon"; a "wind"; a pair of "sparrows" and a pair of "circles"; the "sparrows" and "circles" being in alignment circumferentially of the die and the respective pairs being disposed at right angles to each other.

In witness whereof I have signed this specification.

EARLE M. HUMPHREYS.
